NON-SAG LATCH MEANS FOR OVERHEAD DOORS

Clement E. Petipas, Redondo Beach, Calif.

Application April 4, 1958, Serial No. 726,413

13 Claims. (Cl. 292—99)

This invention relates to doors of the overhead retracting type, such as garage doors, and more particularly relates to the latch means associated therewith for securing the door in overhead horizontal position.

The object of the invention is to provide an improved latch means for doors of the overhead retracting type.

Another object of the invention is to provide a latch means for such type doors which is adapted to secure the door in its overhead horizontal position in such manner as to prevent the door from sagging.

A further object of the invention is to provide a non-sag latch means for doors of the overhead retracting type.

Still another object is to provide a releasable latch means for securing a door of the overhead retracting type in non-sag overhead horizontal position.

Other objects will be apparent as the invention is more fully hereinafter disclosed.

In accordance with these objects, I have devised an improved latch means for securing an overhead door of the retracting type in a non-sag overhead horizontal position, in which latch means a pin means mounted on the outer surface of the door engages a movable cam latch as the door approaches its overhead horizontal position which operates to lift the door out of sag position into non-sag position as the door reaches horizontal position and to releasably secure the door in said non-sag position. The cam latch is sustained in pin-engaging position to be selectively adjustable from a low to an intermediate or to a high position to adapt the latch means for utility with doors having varying degrees of sag.

Before further disclosure of the present invention, reference should be made to the accompanying drawings wherein one specific embodiment of the improved latch means of the present invention is illustrated by way of example but not by way of limitation.

In the drawings:

Fig. 1 is a sectional side elevational view of a garage door of the overhead retracting type provided with the improved latch means of the present invention;

Fig. 2 is an enlarged sectional side elevational view of the upper end of the structure shown in Fig. 1 showing the door moved out of the vertical position of Fig. 1;

Fig. 3 is a view similar to Fig. 2 showing the door in horizontal overhead position with the non-sag latch means of the present invention engaging the door; and

Fig. 4 is a sectional view taken along plane 4—4 of Fig. 1.

Referring to the drawings, a door D of the overhead retracting type provided with retracting means R for moving the door from the vertical position shown in Fig. 1 to the horizontal overhead position shown in Fig. 3, is illustrated. This type of door D is typical of the type commonly utilized as garage doors and in the instant specific embodiment the door D is to be construed as being of the size commonly known as the 2½ door type. The door D and the means R associated therewith are not a

2

part of the present invention except as being necessary and essential thereto.

The present invention relates to the latch means L and the cooperating pin means P, associated with the door D and the means R for latch-securing the door D in non-sag horizontal position.

Referring to these two means more specifically, it can be recognized from the drawings (Fig. 1) that the pin means P is mounted on the outer face of the door D in vertical alignment with the latch means L. In the specific embodiment shown, this vertical alignment is at the approximate vertical center of the door D.

The pin means P is comprised of a double arm bracket 10 having a pin 11 mounted between and on the arms thereof in determined spaced relation to the door D with its pin axis disposed in a horizontal plane parallel to the outer surface of the door D. The pin 11 is mounted at a horizontal level adapted to provide for the engagement of the pin 11 by the hook end 20 of the latch means L as the door D is lifted from the vertical position shown in Fig. 1 to a near-horizontal overhead position. Upon engagement of the pin 11 with the hook end 20 of the latch means L, the slide cam 21 from which the hook end 20 depends is moved from the position shown in Fig. 2 to the position shown in Fig. 3 in which latter position the door D is movably secured or latched into a non-sag horizontal position.

Referring to the latch means L, this means comprises a bracket 31 having a bracket arm 30 mounted thereon on which bracket arm is mounted a slide cam 21 from which depends the hook end 20.

The slide cam 21 is mounted on the bracket arm 30 in such manner as to be movable in the direction of door movement from a low position when the door is in its vertical position to a high position when the door is in its horizontal position and to be releasably latched in said high position with the door D dependingly sustained therefrom in non-sag horizontal position.

To accomplish this result, the slide cam 21 is slideably mounted in a trackway which is inclined upwardly in the direction of door movement to horizontal position. In the specific embodiment shown the bracket arm 30 is comprised of a substantially triangular steel plate having two sides disposed at right angles to each other. The shorter side is secured to the bracket 31 with the longer side uppermost and with the bracket arm 30 sustained vertically at the approximate vertical center of the door. The trackway for the slide cam 21 is provided in the arm 30 by means of the slot 22 formed in the bracket arm 30 in parallel spaced relation to the angular side thereof.

The slide cam 21 is comprised of a pair of steel plates (21a—21b, Fig. 4) also substantially triangular in shape, secured together in parallel spaced relationship by means 55 of rollers 23, 24 and 40. The rollers 23 and 24 engage the trackway provided by the slot 22 and dependingly sustain the cam 21 on the trackway for sliding movement therealong in both directions.

A latch means comprising a notch or transverse groove 60 26 adjacent the upper end of the trackway 22 also is provided, into which the roller 23 passes as the cam 21 reaches high position, as shown in Fig. 3, to thereby dependingly sustain the door D in non-sag position.

Roller 40, mounted on the hook end 20 of the slide 65 cam 21, is a star-type roller and has a dual purpose. As indicated in Fig. 1, the latch means L is mounted in such a position as to permit the hook end 20 of the slide cam 21 to rest upon the upper edge of the door D when the door D is in its vertical position. As the door D is moved from this position toward overhead horizontal position, the roller 40 permits this movement with mini-

mum friction. To eliminate wear on the upper edge of the door D, a bearing plate 41 is provided for the roller 40 to engage. When the pin 11 is engaged in the hook end 20, the star pins on the roller 40 function to retain the pin 11 in the hook end 20.

Referring now more particularly to the slide cam 21 and to the trackway provided therefor by the slot 22, it is believed apparent from Figs. 1, 2 and 3 that the slide cam 21 must be so mounted on the trackway of slot 22 as to be free to assume thereon three different positions.

In the position indicated in Fig. 1, the normal first or rest position, the cam 21 must be free to pivot about the axis of the roller 24 from the position shown in Fig. 2 to the position shown in Fig. 1 upon the return movement of the door D to vertical position. This is provided for in the specific embodiment by providing the lower end of the slot 22 with an upwardly-extending reversing slot portion 25 into which the roller 23 is free to move as the upper edge of the door D engages the hook end 20 in the return movement of the door, while the cam 21 pivots about the axis of the roller 24.

In the reverse movement of the door D to horizontal position, the cam 21 reversely pivots about the axis of the roller 24 as the cam 21 gravitationally returns to full depending position when the door D returns to the position shown in Fig. 2.

After the pin 11 is engaged in the hook end 20 of the cam 21, the eccentric positioning of the hook end 20 on the cam 21 pivots the cam 21 about the axis of roller 23 raising the roller 24 into contact with the trackway provided by the upper edge of the slot 22. In this pivoted position, the weight of the door D is dependingly carried by the cam 21 as the cam 21 is moved upwardly to a position bringing the roller 23 into the notch or transverse groove 26. In other words, the cam 21 has an uplift effect as it moves up the slot 22, under the influence of inward movement of door D. Entrance of the roller 23 into the latch groove 26 effectively latches the door D in horizontal position as the sag weight of the door D holds the cam 21 in seated position in the groove 26, requiring a determined downward pull on the bottom of the door D to lift the roller 23 out of groove 26 engagement over the rounded shoulder 27 to release the roller 23 from latch groove 26.

To adapt the latch means L for utility with doors having varying degrees of sag, the arm 30 is provided with means comprising bolts 35-36 and cooperating aligned openings in bracket 31 and bracket arm 30 to vary the horizontal level of the hook end 20.

In this means the lower bolt 35 functions as the pivot point for the arm 30 and the upper bolt 36 engages one of the arcuately spaced openings 37, 38, 39 in the arm 30. When the bolt 36 engages the opening 37, the arm 30 is mounted in its lowest position with the hook end 20 at its lowest horizontal level. When the bolt 36 engages opening 39, the arm 30 is mounted in its highest position with the hook end 20 at its highest horizontal level. When the bolt 36 engages the intermediate opening 38, the hook end 20 is disposed at an intermediate horizontal level. The spacing between the openings 37, 38 and 39 is selected to provide for a relatively wide range of sag conditions encountered, and the total number of said openings may be increased if desired without essential departure from the invention.

From the drawings it is believed apparent that in operation the non-sag latch means L of the present invention operates substantially as follows:

When the door D is moved upwardly out of the vertical position shown in Fig. 1 by means of handle 50 to the position shown in Fig. 2, the slide cam 21 falls gravitationally from the rest position shown in Fig. 1 to the pin-engaging position shown in Fig. 2 bringing the hook end 20 into a position to engage the pin 11 of the bracket 10 as the door D approaches its overhead horizontal

position. The engagement of the hook-end 20 by the pin 11 causes the slide cam 21 to move upwardly in the slot 22 until the roller 23 engages in the groove 26, which is so located therein to provide for this as the door D reaches full horizontal position. The weight of the door D on the cam 21 secures the door D in full horizontal position until a downward pressure is applied to the bottom end of the door D sufficient to lift the roller 23 out of groove-engaging position and over the rounded shoulder or lip 27 back onto the inclined trackway provided by the slot 22. The door D then can be returned to first (door closure) position by the retracting means R normally provided. When returned to closure position the latch means L assumes the position shown in Fig. 1 wherein the lower roller 23 passes into the re-entrance portion 25 of the slot 22 thereby permitting the star roller 40 of the hook-end 20 of the slide cam 21 to lift upwardly and to rest upon the plate 41.

Bracket 31 and bracket arm 30 are each comprised of heavy steel plate material having the required strength characteristics for the purpose in view, as is also the slide cam 21. It is preferred to comprise the slide cam 21 of two spaced plates 21a-21b, substantially as indicated in Fig. 4, with the rollers 23-24 maintained therebetween by means of bolts 50-50. Various alternative arrangements may be employed, however, without essential departure from the invention, as one skilled in the art will perceive.

Having hereinabove disclosed the present invention generically and specifically and having described and illustrated one specific embodiment thereof, it is believed that many modifications, changes and departures may be made therein without essential departure therefrom, and all such are contemplated as may fall within the scope of the following claims.

What is claimed is:

1. In overhead doors of the retracting type, a latch means for securing the door in a non-sag overhead horizontal position, said latch means comprising a sliding uplift cam provided with a hook end, means sustaining the sliding uplift cam in a position above the horizontal level of the door when in overhead position with the hook end thereof in a position to be engaged by a pin means mounted on the exterior surface of the door as the door approaches its overhead horizontal position, thereby to actuate the sliding uplift cam from a low to a high position as the door reaches overhead horizontal position, and a releasable latch means retaining the cam in said high position, said high position of said cam dependently sustaining the door by said hook end in a non-sag position.

2. The latch means of claim 1 wherein said sliding uplift cam comprises a plate member provided with spaced-apart rollers and wherein said rollers are mounted on an upwardly-inclined trackway, and wherein said trackway is sustained at a horizontal level above the said door when in overhead horizontal position with the upward incline of the trackway extending in the direction of door movement to said overhead position, and wherein said trackway is provided adjacent its upper end with a transverse groove adapted to receive and seat one of said rollers as the door reaches its overhead horizontal position, the weight of the door thereby latching the door in said horizontal position dependently from said hook end of said sliding uplift cam.

3. The latch means of claim 2, said trackway being mounted in a bracket arm extending from a bracket secured to the door header.

4. The latch means of claim 3, said bracket arm being vertically adjustable to vary the position of said hook end.

5. In combination with a door of the overhead retracting type, an overhead latch means for securing the door in non-sag overhead horizontal position, said latch means comprising a hook-ended vertical uplift cam, means sustaining the cam in a position above the door when in its overhead position for its hook end to be engaged by a pin

means disposed on the outer surface of the door as the door approaches said overhead position to thereby engage the cam to move the cam from a low position to a vertically higher position as the door reaches said overhead position, and means at said higher position to secure the cam in non-sag position, said securing means being releasable by the return movement of the door out of its horizontal position to a vertical position.

6. The combination of claim 5, said means sustaining the said cam comprising a bracket mounted above the door, a bracket arm extending horizontally therefrom, an inclined trackway for said cam, spaced roller means on said cam and engaging said trackway, the incline of said trackway being upward in the direction of door movement to overhead position, and wherein said means to secure the said cam in said higher position comprises a transverse groove in said trackway adjacent its upper end adapted to seat one of the said rollers therein.

7. The combination of claim 6 wherein means is provided at the lower end of said trackway for the lower said roller to be displaced vertically upwardly thereby to lift the cam and hook end thereon to a horizontal level at which the said hook end rests upon the top of the said door when it is in its vertical position.

8. A vertical uplift cam means, said cam means comprising a bracket, a bracket arm thereon and means to mount the bracket with the bracket arm extending therefrom in a horizontal plane, a vertically-inclined trackway on said bracket arm, a cam, roller means mounting the cam to be movable along the trackway, and a hook arm depending from said cam in a position to be engaged by a hook end engaging means on an object being moved in the direction of said trackway at a horizontal level below said trackway when said cam is located at the lower end of said trackway, thereby to dependingly sustain the

said object therefrom at the upper end of said trackway at a higher horizontal level.

9. The cam means of claim 8, a transverse groove in said trackway adjacent the upper end thereof adapted to receive and seat the said roller means movably therein.

10. The combination of claim 8 wherein said bracket arm comprises a substantially triangular plate member having two sides substantially at right angles to each other, means sustaining the plate member in a vertical plane with the third side downward, a slot extending along and in spaced relation to said third side, and providing a trackway for said cam.

11. The combination of claim 10 wherein said cam comprises a pair of plate members, a pair of rollers and means securing the two plates together in parallel spaced relationship with the said rollers therebetween in spaced relation adjacent one end of the plate and with the said rollers engaging the said trackway to dependingly sustain the cam therefrom, a hook end on the depending end of said plates, said hook end being provided with a roller means.

12. The combination of claim 11, said last-mentioned roller means comprising a star roller.

13. The combination of claim 10, said slot being provided at its lower end with a vertical reversing slot offset.
